UNITED STATES PATENT OFFICE.

MAX THIER, OF ERFURT, GERMANY.

DISTRIBUTING-GEAR FOR EXPLOSION-MOTORS.

No. 893,675.

Specification of Letters Patent.

Patented July 21, 1908.

Application filed March 28, 1904. Serial No. 200,447.

To all whom it may concern:

Be it known that I, MAX THIER, civil engineer, a subject of the King of Prussia, German Emperor, and residing at Erfurt, 1 Dorotheenstrasse, in the Kingdom of Prussia, German Empire, have invented certain new and useful Improvements in Distributing-Gears for Explosion-Motors, of which the following is a specification.

- 10 0 This invention relates to a distributing gear for explosion-motors, and my improvements in such gears relate to certain combinations and arrangements of parts, as are fully described hereinafter.
- 5 5 In order to make my invention more clear I refer to the accompanying drawings in which similar letters denote similar parts throughout the several views and in which Figure 1 is a view of an explosion-motor
- 10 0 having my improved distributing gear applied to it some parts being shown in section; Fig. 2 is a side-view of the gear as applied to the motor, only the chief parts being shown; Fig. 3 is a frontal-view of a cylinder forming part of the gear, in connection with some other parts which will all duly be referred to in the specification. Fig. 4 is a plan of the parts shown in Fig. 3, and Fig. 5 is a front-view of said parts, the eccentric grooved disk being shown in section. Fig. 6 is a view similar to Fig. 5, showing the position of the rod (f) for actuating the tongue (z).

The distributing gear is intended for motors working after the four-stroke cycle, and the object of my improvements in gears of such a kind is to simplify the means whereby the speed of the motor is regulated. I attain this, first, by providing the cylinder b Figs. 1 and 2 which is keyed to the shaft a, and driven by the same with two circumferential grooves g g' having a crossing w, Fig. 2. The lever c, Fig. 3, actuated by the grooves of this cylinder is fulcrumed at e and has a shoe d Fig. 5 sliding in the grooves g g', in such a manner, that the lever is operated by the mediation of this shoe as soon as the shoe is made to pass from the groove g into the groove g' and reversely. This is effected by a switch or tongue z connected by a pin x, Fig. 6, with a short horizontal rod f guided in the cylinder b and being under the action of a spring y which constantly tends to force the rod f outwards, in the direction to a grooved displaceable disk r attached by a feather and groove to the shaft a. The disk r is coupled by means of pins p, Fig. 3, with

the forked ends p' of an arm p' of a lever p fulcrumed upon a pivot t, and the arm p of said lever is connected by a rod v with the regulator of the motor. Corresponding, therefore, to the movements of the regulator, the rod f is operated either by the disk r or by the spring y, and thus the tongue z will deviate the shoe d either into the groove g or into the groove g' of the cylinder b.

The lever c is combined with another lever h, Figs. 3 and 4, attached to a shaft m. The lever h is uniformly raised and lowered by an eccentric b' forming part of the grooved cylinder b, a shoe h' attached to the lever h taking into said groove. The free end of the lever h extends to below the rod i of the exhaust-valve which is not actuated directly by the lever h but by the mediation of the lever c which is located upon the lever h and has its fulcrum at e upon that lever. The lever c carries again the shoe d and is moved to and fro by the grooves of the cylinder b in just the same manner as before described. The lever c is not only moved laterally by the shoe d but is also moved vertically together with the lever h. The free end of the latter is so shaped (see Fig. 4) that the free end of the lever c is always supported. This end is furnished with an adjustable screw l adapted to act upon the valve-rod i when the position of the lever c is that shown in Fig. 4. If, however, the shoe d of the lever c has been deviated by the switch of the governing-device of the motor, the screw l is kept off the valve-rod i and the valve is thus not actuated at the respective rotation of the shaft a. By thus employing two levers for the two directions of motions, i. e. parallel to the shaft and at right angles to the same, I avoid the necessity of letting one and the same lever make two different motions so that a universal joint as otherwise necessary may be dispensed with.

Having now fully described the nature of my invention what I desire to secure by Letters-Patent of the United States is:

1. In a distributing gear for explosion-motors, the combination with a rotary cylinder having two grooves in its circumferential surface, of a crossing (w) of said grooves, a shoe adapted to slide in said grooves and to be moved by the same, a lever connected with said shoe and adapted to be actuated by the same, and means for causing the shoe to pass through said crossing or to evade the same; another lever adapted to be oscillated

in a plane located at right angles with respect to the first lever and carrying the same, means for oscillating the second lever so as to cause this lever to oscillate the first lever in the same direction, substantially and for the purpose as described.

2. In a distributing gear for explosion-motors, the combination with a rotary cylinder having two grooves in its circumferential surface, of a crossing (w) of said grooves, a shoe adapted to slide in said grooves and to be moved by the same, a lever connected with said shoe and adapted to be actuated by the same, and means for causing the shoe to pass through said crossing or to evade the same; another lever adapted to be oscillated in a plane located at right angles with respect to the first lever and carrying the same, means for oscillating the second lever so as to cause this lever to oscillate the first lever in the same direction; a valve-rod having its end over the end of the second lever and terminating over the same in such a distance that said lever cannot contact with said valve-rod, the first lever being adapted to be displaced so far that its end gets below the said valve-rod so as to actuate the same when raised by the second lever, substantially and for the purpose as described.
3. In a distributing gear for explosion-motors, the combination with a rotary cylinder,

having two grooves in its circumferential surface, of a crossing (w) of said grooves, a shoe adapted to slide in said grooves and to be moved by the same, a lever connected with said shoe and adapted to be actuated by the same, and means for causing the shoe to pass through said crossing or to evade the same; another lever adapted to be oscillated in a plane located at right angles with respect to the first lever and carrying the same, means for oscillating the second lever so as to cause this lever to oscillate the first lever in the same direction; a valve-rod having its end over the end of the second lever and terminating over the same in such a distance that said lever cannot contact with said valve-rod, the first lever being adapted to be displaced so far that its end gets below the said valve-rod so as to actuate the same when raised by the second lever, the free end of the first lever having an adjustable screw so located as to be adapted to actuate the valve-rod, substantially and for the purpose as described.

In witness whereof I have hereunto set my hand in presence of two witnesses.

MAX THIER.
